UNITED STATES PATENT OFFICE.

RALPH HARRIS, OF KANSAS CITY, MISSOURI.

GOVERNOR.

SPECIFICATION forming part of Letters Patent No. 745,056, dated November 24, 1903.

Application filed July 28, 1902, Serial No. 117,243. (No model.)

To all whom it may concern:

Be it known that I, RALPH HARRIS, a citizen of the United States, and a resident of Kansas City, in the county of Jackson and State of Missouri, have invented a new and Improved Governor, of which the following is a full, clear, and exact description.

The invention relates to governors used for various purposes—for instance, for controlling the amount of gasolene for explosive-engines.

The object of the invention is to provide a new and improved governor which is composed of but few parts, not liable to easily get out of order, and arranged to work with the greatest precision and sensitiveness to accurately control the speed of the device on which it is used.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a sectional side elevation of the improvement applied to the inlet-valve for a gasolene-pump of an explosive-engine—such, for instance, as shown and described in the application for Letters Patent of the United States filed under even date herewith, Serial No. 117,242. Fig. 2 is a plan view of the improvement, parts being in section; and Fig. 3 is a sectional side elevation of the exhauster.

The frame A, on which the governor is mounted, is provided with a bearing A', in which is arranged to turn the hub B' of a wheel B, on which is secured or formed a pulley C, connected by belt with a driven part of the device on which the governor is used, so as to rotate the wheel B. The latter is formed with an axial cylinder B², in which is mounted to slide lengthwise a piston D, connected at its outer end with a bell-crank lever E, connected by a link E' with an arm E², held on the stem of an admission-valve F, arranged in the suction-pipe G of a gasolene-pump H,

discharging into a supply and mixing pipe I for conducting the explosive mixture into the working cylinder of the engine.

The inner end of the piston D is pressed by a spring J, the tension of which can be regulated by a screw-plug K or other suitable means, the said spring serving to hold the piston D in an outermost position against atmospheric pressure exerted on the outer end of the piston. The screw-plug K, as shown, serves to close the end of the cylinder opposite the one through which the piston D projects.

The cylinder B², between the inner end of the piston D and the inner end of the screw-plug K, is connected by an annular narrow passage-way B³ with an exhaust-chamber B⁴, preferably divided by partitions B⁵ into a plurality of compartments, as plainly indicated in Fig. 3, the said exhaust-chamber being connected by ports B⁶ with the peripheral face of the wheel B, it being sufficient to provide a single port B⁶ for each compartment.

The operation is as follows: When the engine or other device on which the governor is applied is rotated, then a rotary motion is given to the wheel B, so that the air in the exhaust-chamber B⁴ is exhausted therefrom by centrifugal force, the air passing from the chamber through the ports B⁶ to the outside of the wheel. As the air is exhausted from the chamber B⁴ it is evident that a like exhausting of air takes place in the cylinder B², as the latter is connected by the passage-way B³ with the chamber B⁴, and consequently the atmospheric pressure exerted against the outer end of the piston D causes the latter to slide inward against the tension of the spring J and in doing so causes a swinging of the bell-crank lever E to actuate the valve F for cutting off the supply of gasolene to the pump H as the speed of the governor-wheel B increases beyond a normal rate of speed. When the speed of the wheel B decreases, then air passes back into the chamber B⁴ and cylinder B² by way of the ports B⁶ and passage-way B³, so that pressure against the inner end of the piston D is increased to allow the spring J to push the piston D correspondingly outward.

for opening the valve F to a normal open position. When the wheel B stops completely, then the piston D is pushed by atmospheric pressure outward to such an extent that the 5 valve F is moved into a closed position.

By having the exhaust-chamber divided into compartments the air contained in the exhaust-chamber is not liable to lag behind the speed of the revolving governor and a full 10 effect of the centrifugal action of the revolving wheel is obtained.

It will be seen that the partitions B⁵ of the wheel B are disposed at a tangent to the axis of rotation, the outer ends of said partitions 15 extending tangentially backward with reference to the direction of the revolution of the wheel. The peripheral openings B⁶ are at the points of the angles formed by the union of the partitions B⁵ with the inner periphery of the wheel B. Hence the inclination of the air within the peripheral chamber to lag behind the speed of the revolving governor will cause said air to be wedged, as it were, into 20 said angles with its greatest pressure or density at these points. For that reason the openings B⁶ are preferably located at the rear points or ends of the chambers B⁴. Again, if the governor be suddenly stopped the momentum of the air within the chambers B⁴ 25 will cause it to be jammed or packed, as it were, into the forward ends of the said chambers, thereby making the vacuum within said chambers the greatest at the points where the openings B⁶ are located. Thus it appears 30 that the disposing of the partitions B⁵ and the locating of the openings B⁶ as shown conspire to cause the air at a given speed to be most rapidly exhausted from said chambers B⁴ when the wheel B is in motion and to 35 40 be most quickly drawn again into said chambers to relieve the vacuum when the motion of the wheel is stopped or retarded. In the ordinary blast-fan the fan proper is located in a stationary case, and when the fan is revolved to impart centrifugal force to the air within said case to expel the air therefrom the moving body or mass of air constantly adheres in a measure to the inner walls 45 of the stationary case by frictional contact 50 therewith, and consequently more power is required to impart a given speed to the fan because of said frictional contact. My fan differs from all these fans in that the entire chamber containing the air is revolved, so 55 that I entirely avoid the frictional contact just referred to.

Having thus described my invention, I claim as new and desire to secure by Letters Patent—

60 1. A governor comprising a revoluble case having an axial cylinder revolving therewith and provided with an exhausting-chamber for the cylinder, and a piston in the said cylinder, connected with the part to be governed, as set forth.

2. A governor comprising a revoluble hollow wheel inclosing an exhausting-chamber having peripheral outlets and with an axial cylinder revolving with the wheel and connected with the exhausting-chamber, and a 70 piston slidable in the cylinder and connected with the part to be governed, as set forth.

3. A governor comprising a revoluble circular shell inclosing an exhausting-chamber having peripheral outlets, an axial cylinder 75 revolving with said shell and connected with the exhausting-chamber, a piston slidable in the cylinder and connected with the part to be governed, and a spring pressing the said piston, as set forth.

4. A governor comprising a revoluble wheel or shell forming the inclosing walls of an exhausting-chamber having peripheral outlets and with an axial cylinder forming a rigid extension of said shell connected with the exhausting-chamber, a piston slidable in the cylinder and connected with the part to be governed, a spring pressing the said piston, and means for regulating the tension of the 85 said spring, as set forth.

5. In governors, a revoluble wheel having an air-chamber therein, transverse partitions within said chamber forming the same into a plurality of compartments, each compartment having an opening in communication with 90 the outer air, a central cylinder in the wheel and in communication with said chamber, a piston in the cylinder and connected to the part to be governed, and means for revolving said wheel to expel the air from said chamber by centrifugal pneumatic force, whereby 95 to create a vacuum within said chamber to influence the piston, for the purpose set forth.

6. In a governor, a revoluble wheel or shell having a central vacuum-cylinder, and a ring-shaped chamber surrounding said cylinder and in communication therewith, transverse partitions within said chamber dividing the same into a plurality of compartments each having an opening leading into the outer air, 105 said partitions being tangentially disposed with their outer ends inclined backwardly with respect to the direction of revolution of the wheel, said openings being located in the rear portions of their respective chambers, a 110 spring-pressed piston in the cylinder connected to the device to be governed, and means for revolving said wheel to expel the air from the chamber therein by centrifugal force, to create a vacuum within said chamber to influence the piston, for the purpose 115 set forth.

7. In a governor, a revoluble wheel or casting having a central vacuum-cylinder, and a ring-shaped chamber surrounding said cylinder and in communication therewith by means of an annular diametrical slit, transverse partitions within said chamber dividing the same into a plurality of compartments, each having an opening leading into the outer air, a 125 130

piston in said cylinder, said piston being influenced by the vacuum within the cylinder of the revoluble wheel and being connected with the part to be governed, and a spring in
5 said cylinder, located between the piston and an adjustable stop, for the purpose set forth.

In testimony whereof I have signed my

name to this specification in the presence of two subscribing witnesses.
